(57) **CLAIM**

The ornamental design for a charger for electronic device, as shown and described.

DESCRIPTION

FIG. 1 is a perspective view of a chager for electronic device showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a perspective view of a second embodiment of my design;

FIG. 7 is a top plan view thereof;

FIG. 8 is a front elevational view thereof;

FIG. 9 is a right side elevational view thereof; and,

FIG. 10 is a left side elevational view thereof.

1 Claim, 6 Drawing Sheets
